UNITED STATES PATENT OFFICE.

MICHAEL BETKE, OF DENVER, COLORADO.

AUTOMATIC RAIL-JOINT FASTENING.

Application filed March 19, 1926. Serial No. 95,856.

An object of this invention is to provide improved means for tightening the nuts of rail joint fastenings by means of devices carried by said joint and operated by the passage of wheels thereover.

A further object of this invention is to provide a hinged construction of operating plate and impact head in an automatic rail-joint fastening.

10 My invention consists in the construction, arrangement and combination of elements hereinafter set forth, pointed out in my claims and illustrated by the accompanying drawings, in which—

15 Figure 1 is a side elevation of abutting end portions of railway rails to which my improvements are applied, a portion of a wheel being shown surmounting said rails. Figure 2 is a plan of the same, the wheel 20 being omitted. Figure 3 is a cross section on the indicated line 3—3 of Figure 2. Figure 4 is a cross section on the indicated line 4—4 of Figure 2. Figure 5 is a detail cross section, on an enlarged scale, of the 25 operating plate and attached devices. Figure 6 is a detail side elevation of one of the units of my improvement, certain parts being broken away to expose concealed elements.

30 In the construction of my improvement as shown, the numeral 10 designates either portion of abutting railway rails, forming a joint. Fishplates 11, 12 are mounted on said rails and overlap said joint in a common manner, the web or vertical portion of the fishplate 12 being of materially greater thickness than that of the fishplate 11, so as to fill the space at one side of the rails and bring the outer face of the fishplate 12 40 into the same vertical plane as the outside edge of the tread of said rails. The rails 10 and fishplates 11 and 12 are formed with registering bolt holes and bolts 13, in this instance four in number, are mounted 45 through said holes with their threaded end portions extending beyond the fishplate 12. Nuts 14, each formed with a ratchet wheel base portion 15, are threaded on the bolts 13 and are adapted to be employed to clamp 50 the fishplates to the rail portions. Recessed blocks 16, in this instance five in number, are mounted on the outer face of the fishplate 12 between the bolts 13 and are secured to 55 said fishplate by rivets 17, the inner heads of said rivets being countersunk in the fishplate to permit of a smooth and uniform

ruptured seating of said fishplate against the web of the rail portions. The blocks 16 are evenly spaced apart with their edges parallel to form slide bearings and the upper ends of said blocks project slightly above the edge of the fishplate 12 and bear against the outer edge of the tread of the rail portions. The blocks intermediate the end portions of the fishplate are alike in 60 form and are each provided with two parallel recesses opening against the face of said fishplate while the end blocks are narrower than the intermediate blocks and have but a single recess each. Plates 18, in this 65 instance four in number, are each formed with an elongated hole 19 and a laterally projecting head 20 of less width than the plate and are slidingly mounted in the slide 70 bearings provided between the edges of the blocks 16, the bolts 13 passing through the elongated holes 19 and said plates being positioned by the ratchet wheel portion 15 of the nuts 14 against the outer face of the fishplate 12. Impact heads 21, of the same 75 width as the plates 18, are formed with curved upper faces adapted to be engaged by the tread portions of wheels and are also formed with downwardly-extending arms 22 adapted to embrace the heads 20 of the 80 plates 18. Pins or rivets 23 pass through registering holes in each of the heads 20 and the embracing arms 22, thus hingedly securing an impact head 21 to each of the plates 18. The upper outer edge of each head 20 85 is curved concentric with the axis of its pin 23 and the top of said head is inclined slightly at a tangent to said curve, to the end that the impact head 21 may be rotated about the pin 23 to the position shown in 90 dotted lines in Figure 5 and also to provide that said impact head may seat directly on the head 20 when in upright position rather than on the ends of the pin 23. Detents 95 24, of elbow shape, are each formed with a projecting stud 25 adjacent the elbow and are secured to the plates 18 with the short arm of said detent below and engaging the 100 projecting lower margin of the head 20 by means of said stud, which passes through a hole in the plate 18 and is riveted behind said plate. The longer arm of the detent 24 extends vertically along the face of the plate 18 adjacent the ratchet wheel portion 15 of the nut 14 and is formed with teeth 105 26 adapted to engage one or more of the teeth of the ratchet 16. Angle-bars 27, having

ing one leg vertical and of a length equal to the width of a slide bearing and the other leg horizontal, notched to clear the short arm of the detent 24 and of a length greater than the width of a slide bearing, are mounted transversely of each slide bearing with the horizontal leg beneath and engaging the lower ends of the arms 22 and extending through openings in the side margins of the blocks 16 into and across the recesses within said blocks, as is clearly shown in Figure 6. Expansive coil springs 28 are confined within the recesses in the blocks 16 and each spring has one end bearing against an end of the angle bar 27 and the other end engaging the bottom of its recess or bearing against a device adjacent thereto. The springs 28, being mounted under some compression, tend at all times to force the angle bar 27 upward, which bar, through its engagement with the arms 22 tends to lift the impact head 21, attached plate 18 and detent 24. Interposed between one end of the angle bar 27 and the end of its respective spring 28 is a flat bar 29 which extends laterally along the lower face of the angle bar and engages beneath the end of the short arm of the detent 24, to the end that any displacement of the detent 24 will cause increased compression of a spring 28 which will tend to restore the detent to its original position at all times. A pawl 30 is pivoted for rocker bearing against the bottom of the spring recess on the detent side of the slide bearing and is positioned in the block 16 by means of a pin or studs 31, the toe of the pawl being extended slightly upward and laterally across the lower end of the plate 18 to engagement with one of the teeth of the ratchet wheel 15 to prevent rotation tending to unscrew the nut 14, while the heel of the pawl is formed to a flattened bearing adapted to receive the lower end of one of the springs 28 and be depressed thereby.

When my device is mounted for practical use, the nuts 14 are tightened with the plates 18 in their lowermost position and the springs 28 under compression as illustrated by three of the devices in Figure 1. Unscrewing of the nuts 14 is prevented by ratchet engagement of the pawls 30, but if and when the pressure exerted against the plate 18 by the nut 14 is diminished and the nut tends to loosen, the pressure of the springs against the angle bar 27 forces said bar upwardly and thereby raises the impact head above the top of the rail head, the detent 24 ratcheting upwardly into a new engagement with the teeth of the ratchet wheel 15. Passage of a car, locomotive or the like along the rails will again depress the impact head through engagement of said head with the tread portion of a wheel, the detent, in its downward movement, rotating and tight-

ening the nut 14 which ratchets past the pawl 30 into new engagement with said pawl. This operation is repeated until the nut 14 is tightened sufficiently to hold the plate 18 against the pressure of the springs 28 and thus insures that the rail-joint is always tightly bolted together. If for any reason the wheels should be moving laterally of the rails and the edge of one of said wheels should strike the inner face of the impact head 21, said head would rotate outwardly about the pin 23, the squared outer, lower corners of the arms 22 depressing the angle bar 27 against the springs 28, said displacement of the springs tending to return the impact head to its upright position when the wheel has passed. It is to be noted that all strains and pressures are transmitted from surface to surface, the pins, rivets and studs in the operating devices serving only as pivots.

I claim as my invention—

1. An automatic rail-joint fastening comprising a fishplate having its outer face in the same vertical plane as the outer edge of the rail tread, bolts connecting said fishplate and rails, ratcheted nuts on said bolts outside said fishplate, laterally projecting blocks on said fishplate intermediate said bolts, operating plates apertured to receive said bolts mounted for vertical reciprocation between said blocks and adapted to be contained between said ratcheted nuts and the face of said fishplate, means carried by said plates and engaging said ratcheted nuts for rotating said nuts in a tightening direction, means carried by said blocks for preventing reverse rotation of said nuts and means also carried by said blocks for elevating said operating plates and attached devices.

2. In a device of the character described having abutting rail portions, fishplates adapted to overlie the joint between said rail portions and bolts adapted to clamp said fishplates to said rails, the combination of a fishplate having its outer face in the same vertical plane as the outer edge of the rail tread, vertical slide bearings on the outer face of said fishplate and intersected by said bolts, ratcheted nuts on said bolts, operating plates mounted in said slide bearings between said ratcheted nuts and the outer face of said fishplate, an impact head pivotally secured to each of said operating plates, means carried by said operating plates for rotating the ratcheted nuts in a tightening direction, means for preventing reverse rotation of said nuts and yielding means for maintaining the operating plates and attached devices in raised position.

3. In a device of the character described having abutting rail portions forming a joint, fishplates adapted to overlie said joint and bolts connecting said rails and fish-

- plates, the combination of a fishplate having its outer face in the same vertical plane as the outer edge of the rail tread, vertical, laterally projecting blocks on the outer face of said fishplate spaced to form slide bearings intersected by said bolts, expansive coil springs within said blocks, operating plates mounted for vertical reciprocation in said slide bearings between ratcheted nuts carried by said bolts and the face of said fishplate, means carried by said plates for rotating said ratcheted nuts, means for preventing reverse rotation of said nuts and means transversely of the slide bearing engaging said operating plates and supported by said springs for maintaining said operating plates and attached devices in raised position.
4. In a device of the character described, an operating plate formed with an elongated aperture and a laterally projecting head, an impact head seated on and pivotally secured to said laterally projecting head and a detent pivotally mounted on said plate and engaging beneath said laterally projecting head.
5. In a device of the character described,
- a vertical slide bearing, an operating plate mounted for vertical reciprocation in said bearing, an impact head secured to said plate and adapted for lateral displacement relative thereto, expansive coil springs housed at either side of said bearing, said springs comprising a yielding mounting for said operating plate and attached devices, one of said springs also being adapted to position and return a detent pivoted on said plate, the other of said springs being adapted to position and return a pawl.
6. In a device of the character described, an impact head formed with a downwardly opening yoke adapted to embrace and be pivotally secured to the head of an operating plate and yielding means engaging beneath the arms of said yoke adapted to resist displacement of the impact head relative to the operating plate and restore said impact head to its operative position when displaced.

Signed at Denver, in the county of Denver and State of Colorado this 23rd day of February, 1926.

MICHAEL BETKE.
